UNITED STATES PATENT OFFICE

WILLIAM I. HOOD, OF NORWALK, OHIO, ASSIGNOR OF ONE-HALF TO JOHN W. CHESROWN, OF NORWALK, OHIO.

BURIAL-CRYPT.

No. 858,070.

Specification of Letters Patent.

Patented June 25, 1907.

Application filed March 14, 1907. Serial No. 362,399.

To all whom it may concern:

Be it known that I, WILLIAM I. HOOD, a citizen of the United States, residing at Norwalk, in the county of Huron and State of Ohio, have invented a new and useful Burial-Crypt, of which the following is a specification.

This invention has relation to burial crypts and it consists in the novel construction and arrangement of its parts as hereinafter shown and described.

The object of the invention is to provide a community crypt having a hall-way or lobby of sufficient size to accommodate the funeral attendants and which will protect them during the services, from extreme temperatures in the weather and also from storms.

Figure 1 is a side elevation of the crypt. Fig. 2 is a plan view of the same. Fig. 3 is a front elevation of the catacomb. Fig. 4 is a vertical sectional view of the catacomb, and Fig. 5 is a front elevation of a modified form of the crypt.

The exterior walls are provided with air chambers into which the ports of the catacombs communicate; these air chambers lead to a common point of escape at or near the highest point in said outer wall, thus conducting any gases, that might accumulate, out into the air at a high elevation, the gases are disseminated into the atmosphere far above the ground. These air chambers also serve to keep the walls dry, as the current of air constantly passing through them absorbs any dampness that might accumulate therein.

The crypt comprises the hall or lobby 1 of sufficient size to accommodate a funeral train. The said hall is provided with one or more ports or gates 2 and in the preferred form (see Fig. 2) is provided on each side of said port 2 with an urn-room and toilet. The urn-room is fitted with seamless concrete lockers, as receptacles for ashes of those who may be cremated.

The catacombs 4, 4 are arranged in vertical rows, tier upon tier, and separated from each other by homogeneous partitions, preferably of concrete cement and homogeneous tops; the lower surface of the floor of one set of catacombs forming the tops of the next set of catacombs below. Said floor being homogeneous and preferably of concrete cement.

The rear ends are provided with the valved-ports 5, which communicate with the air spaces or passage 6 in the outer walls of the crypt. The said air passage 6 has an outlet at or near the top of the outer structure, consequently should gas generate within the catacombs, as soon as the pressure in the catacombs becomes greater than the atmospheric pressure, the said gas escapes through the ports 5, and the air passage 6, and consequently the catacombs will not burst or become ruptured as the result of excessive internal pressure.

The front ends of the catacombs are provided with the valve-ports 7 and it is through these ports that the air is exhausted from the interior of the catacombs, when the casket is first deposited therein. At the base of each tier of catacombs is provided a shelf 8, which extends longitudinally of the tier, and which has its upper surface in the same plane as the bottom of the catacombs. The said shelves may be used for the purpose of supporting floral designs and appropriate emblems, and at the same time they serve as guides in directing the casket into the catacomb. The said catacombs are so spaced from the walls of the crypt that in event of settling of said walls, the catacombs will not be disturbed, and hence will not become cracked or ruptured.

In the form of the invention as illustrated in Fig. 5 of the drawing, two sets of catacombs are provided, one on each side of the hall-way, and the hall-way is provided at each end with portals 2, 2 through which the funeral train may pass. The hall-way is provided with portals at each end of the structure to provide light, an abundance of ventilation, as well as, the means of entrance and exit of funeral trains. The hall-way in Fig. 5 of the drawing is further provided with light by means of skylight glass 9 in roof over said hall-way.

Having described my invention what I claim as new and desire to secure by Letters-Patent is:

1. A burial crypt comprising a structure with a reception hall-way, seamless catacombs arranged therein and spaced from the walls thereof wherebv an air passage is formed, said catacombs being provided with valve-controlled ports at their ends which

communicate with said air passage, said passage having an outlet at, or near, the top of the structure.

2. A burial crypt comprising a structure with a reception hall-way, seamless catacombs located therein and spaced from the walls thereof whereby an air passage is formed, said catacombs being provided with valve-controlled ports at their rear ends which communicate with said air passage, said passage being provided with an outlet at or near the top of the structure, also valve-controlled ports at the front ends of the catacombs through which the air may be exhausted therefrom after the same are sealed.

3. A burial crypt comprising a structure with a reception hall-way, seamless catacombs located therein and spaced from the walls thereof whereby an air passage is

formed, said catacombs being provided with valve-controlled ports at their rear ends which communicate with said air passage, said passage being provided with an outlet, at or near the top of the structure, also valve-controlled ports at the front ends of the catacombs through which the air may be exhausted therefrom after the same are sealed and a horizontal shelf in front of each row of catacombs, the upper surfaces of the shelves lying in the same plane as the upper surfaces of the bottoms of the catacombs.

In testimony that I claim the foregoing as my own, I have hereto affixed my signature in the presence of two witnesses.

WILLIAM I. HOOD.
